UNITED STATES PATENT OFFICE.

STEPHEN J. BROWN, OF TROY, NEW YORK.

DESIGN FOR A VENTILATOR.

SPECIFICATION forming part of Design No. 23,030, dated January 30, 1894.

Application filed December 13, 1893. Serial No. 493,586. Term of patent 14 years.

To all whom it may concern:

Be it known that I, STEPHEN J. BROWN, a citizen of the United States, residing at Troy, in the county of Rensselaer and State of New York, have invented and produced a new and original Design for Ventilators, of which the following is a specification, reference being had to the accompanying drawing, showing in a single figure a view in perspective of a 10 ventilator embodying my design.

The ventilator comprises a vertical cylindrical shaft A—, surmounted by an end-flange B—, a hood C—, and shield D—, having the edge-flanges D'—. The flange and hood are so 15 shaped and placed relatively to each other, as to form parts of a spheroidal body, and are inclosed by the shield D— having the edge-flanges D'—. The shield has the form and appearance of the rim of a flanged wheel.

The device, as an entirety, when seen in 20 side elevation has the form and shape of a spheroidal body mounted upon the upper end of a vertical cylinder and inclosed by the rim of a flanged wheel, the axis of the rim being vertical, and the spheroidal body projecting 25 above and below the rim.

What I claim as new, and desire to secure by Letters Patent, is—

The design for a ventilator herein shown and described.

In testimony whereof I have hereunto set my hand this 11th day of December, 1893.

STEPHEN J. BROWN.
